UNITED STATES PATENT OFFICE

149,810

DESIGN FOR A COMBINATION FLASHLIGHT AND COMPACT

John N. Graef, Winnetka, Ill., assignor to Swain
Nelson Engineering and Equipment Company,
Glenview, Ill., a partnership

Application October 16, 1946, Serial No. 133,997

Term of patent 7 years

(Cl. D86—10)

To all whom it may concern:

Be it known that I, John N. Graef, a citizen of the United States, residing at Winnetka, in the county of Cook and State of Illinois, have invented a new, original, and ornamental Design for Combination Flashlight and Compact, of which the following is a specification, reference being had to the accompanying drawing, forming a part thereof.

Figure 1 is a perspective view of the combination flashlight and compact, with the compact cover closed.

Figure 2 is a perspective view of the combination flashlight and compact, with the compact cover open.

I claim:

The ornamental design for a combination flashlight and compact, substantially as shown.

JOHN N. GRAEF.
